UNITED STATES PATENT OFFICE

FRANCESCO CATIGNANI, OF INDIANOLA, PENNSYLVANIA

CHOCK FOR RAILWAY CARS

Application filed February 28, 1929. Serial No. 343,390.

The present invention relates to improvements in brakes and has reference more particularly to a chock for attachment on the head of a rail and for engagement with one of the wheels of a railway mine car whereby said car will be absolutely prevented from moving on the rail while the miner occupies a dangerous position during the filling of the car in the mine.

10 It has been experienced that the ordinary brakes of a railway mine car do not positively hold the car against movement and frequently during the loading of the car in the mine, the jarring action will tend to release the brake and in some instances cause serious injury to the workmen standing in a position adjacent the car during the filling of the same.

It is therefore one of the principal aims 20 of my invention to provide a safety appliance that will absolutely prevent movement of the car, the appliance being of such construction as to permit the same to be readily and easily attached or detached to the rail and for a 25 wedging engagement between the head of the rail and one of the wheels of the car.

A further object is to provide a chock of the above mentioned character that is capable of a swinging movement in a horizontal plane 30 whereby to properly position the chock after the supporting means therefore have been clamped on the head of the rail so that the chock may be efficiently used regardless whether the rail is straight or curved.

35 A still further object is to provide a chock of the above mentioned character that is simple in construction, inexpensive, strong and durable and further well adapted for the purposes for which it is designed.

40 Other objects and advantages of the invention will become apparent from the following description when taken in connection with the accompanying drawing.

45 In the accompanying drawings wherein like reference characters indicate corresponding parts throughout the same;

Figure 1 is a side elevation of the chock embodying my invention showing the same 50 in use.

Figure 2 is a top plan view of the chock attached on a rail.

Figure 3 is a vertical sectional view taken approximately on the line 3—3 of Figure 2 looking in the direction of the arrows.

55 Figure 4 is a transverse section taken substantially upon the line 4—4 of Figure 3 looking downwardly.

Figure 5 is a detail perspective view of the chock per se; and

60 Figure 6 is a detail perspective view of one of the rail engaging clamps forming a salient part of the present invention.

In the drawings wherein for the purpose of illustration is shown the preferred embodiment of my invention, the numerals 1 and 2 designate a pair of complementary clamps adapted to engage the opposite sides of the head of a rail A in the manner as clearly 65 shown in Figure 3, and to this end, the opposed faces of the lower portions of these clamps are formed with the horizontally extending channels 3 whereby to form the inwardly directed lips 4 that engage with the underside of the head of the rail. The upper 70 faces of the coacting clamps are substantially flat and the upper portions of the clamps are formed with registering transverse openings 5 to accommodate the elongated rod 6.

75 A cotter pin 7 extends through a suitable opening formed in the inner end portion of the rod 6 and a washer 8 encircles the inner end portion of this rod for disposition between the outer face of the clamp 2 and the cotter pin 7 in the manner as clearly shown in Figure 3.

An additional cotter pin 9 extends through a transverse opening formed in the outer end portion of the rod 6 and a washer 10 encircles the outer end portion of the rod 6 for disposition against the inner side of the cotter pin.

85 An expansible coil spring 11 encircles the outer end portion of the rod 6 for disposition between the outer face of the clamp 1 and the washer 10 and this coil spring co-operates 90 with the pin 7 to normally urge the coacting clamps 1 and 2 together whereby to positively maintain the same in engagement with the head of the rail A as suggested very clearly 95 in Figure 3 of the drawings.

A pin 12 is formed on the intermediate portion of the rod 6 and the same extends upwardly between the inner opposed faces of the coacting clamps 1 and 2, the upper end of this pin 12 being threaded as indicated at 13 for a purpose to be presently described. The inner opposed faces of the upper portion of the coacting clamps 1 and 2 are grooved as indicated at 14 to accommodate the cylindrical pin 12 and this feature is clearly shown in Figure 4 of the drawings.

For the purpose of separating the coacting clamps to facilitate the disengagement of the same from the head of the rail A, I provide the lever 15 that is formed at its inner end with a yoke 16. A suitable handle 17 is used on the outer end of this lever. A pair of spaced apertured lugs 18 extend outwardly from the outer face of the clamp 1 and the free ends of the arms of the yoke 16 are disposed adjacent the outer sides of the respective apertured lugs and the outer ends of these arms of the yoke 16 are also formed with apertures to communicate with the apertured lugs for the purpose of receiving the pivot pin 19 in the manner as more clearly suggested in Figure 4.

Obviously by swinging the lever 15 upwardly and then pulling outwardly thereon, the jaw or clamp 1 is moved outwardly along the rod 6 against the tension of the coil spring whereby to disengage the same from the head of the rail and when the clamp 1 is disengaged from the head of the rail, the complementary clamp 2 can also be readily and easily disengaged from the head of the rail.

Forming a salient part of the present invention is the chock denoted generally by the numeral 20, the same comprising a substantially rectangular shaped block 21 that is formed at one end with the curved wheel engaging face 22.

A handle 23 extends outwardly from the opposite end of the block at the upper portion thereof and the outer end portion of the block 21 is cut out at its lower corner to accommodate the clamps 1 and 2, the upper face of the cut out portion being adapted to rest on the upper flat faces of the spring pressed clamps 1 and 2 while the bottom face of the major portion of the block rests on the upper face of the rail.

The outer end portion of the block 21 is formed with the vertical bore 24 to accommodate the unthreaded lower end portion of the stem or pin 12 and in this manner, the chock 20 is capable of swinging movement in a horizontal plane. The purpose of adjusting the chock 20 is to adapt the chock to various rails that may be either straight or curved and in Figure 2 of the drawings, I have shown in dotted lines, a curved rail and the position of the chock with respect thereto.

For the purpose of securing the chock 20

in its properly adjusted position, I provide a nut 25 that is threaded on the upper threaded end 13 of the stem or pin 12 and the bottom face of this nut engages with the upper face of the block 21. A laterally extending handle 26 is associated with the nut 25 for manually actuating the same. It is obvious that when the handle 26 is turned in one direction, the nut 25 will move upwardly on the threaded end 13 so as to unclamp the block 21 and permit the handle 23 to be grasped and move the chock 20 so that the wheel engaging face 22 will be in proper position to engage with the tread of the wheel B of a mine car C in the manner as clearly suggested in Figure 1.

When the parts are arranged as shown in Figure 1, the chock 20 will absolutely hold the car C from moving along on the rails A, in one direction, and after the car has been loaded the chock can be readily and easily removed from engagement with the wheel B and the entire device disengaged from the rail.

It will thus be seen from the foregoing description, that I have provided a chock that will at all times be positive and efficient in carrying out the purpose for which it is designed and due to its simplicity, the parts can be readily and easily adjusted. It will also be apparent from the foregoing description, that it is not necessary to alter the construction of the rail or the wheels of the car to accommodate my improved chock.

While I have shown the preferred embodiment of my invention, it is to be understood that minor changes in the size, shape, and arrangement of parts may be resorted to without departing from the spirit of the invention or the scope of the appended claims.

What I claim is:

1. In a device of the class described, a vertically disposed stem, means for securing the same on the head of a rail, a chock mounted on the stem for swinging movement in a horizontal plane, said chock being formed with a wheel engaging face at one end, and means for clamping the chock in a predetermined adjusted position.

2. In a device of the class described, a vertically disposed stem, means for securing the same on the head of a rail, a chock mounted on the stem for swinging movement in a horizontal plane, said chock being formed with a wheel engaging face at one end, and means for clamping the chock in a predetermined adjusted position, said means including a nut threaded on the upper end of the stem and adapted for clamping engagement with the upper face of the chock.

3. In a device of the class described, a pair of coacting rail head engaging clamps, means for detachably securing the clamps on the head of a rail, a vertically disposed stem carried by said securing means and extending

upwardly between said clamps, a chock for rest upon the head of the rail, one end of the chock being formed with a wheel-engaging face, the other end of said chock being cut out for rest upon said clamps, said chock being mounted on the stem for swinging movement in a horizontal plane, and means for clamping the chock against the swinging movement.

4. In a device of the class described, a pair of coacting rail head engaging clamps, means for detachably securing the clamps on the head of a rail, a vertically disposed stem carried by said securing means and extending upwardly between said clamps, a chock for rest upon the head of the rail, one end of the chock being formed with a wheel-engaging face, the other end of said chock being cut out for rest upon said clamps, said chock being mounted on the stem for swinging movement in a horizontal plane, and means for clamping the chock against the swinging movement, said means comprising a nut threaded on the upper end of the stem and adapted to engage with the upper face of the chock and secure the same in binding engagement with the upper faces of the clamps.

5. In a device of the class described, a pair of complementary rail head engaging clamps, a rod extending transversely through the clamps above the rail, means associated with the rod for cooperation with the clamps to maintain the latter in locked engagement with the head of the rail, a chock having a wheel-engaging face at one end, and means for mounting said chock for swinging movement in a horizontal plane on the top of the clamps as and for the purpose described.

6. In a device of the class described, a pair of complementary rail head engaging clamps, a rod extending transversely through the clamps above the rail, means associated with the rod for cooperation with the clamps to maintain the latter in locked engagement with the head of the rail, a chock having a wheel-engaging face at one end, and means for mounting said chock for swinging movement in a horizontal plane on the top of the clamps, said means including a stem carried by the rod and extending upwardly between the coacting clamps, the upper end of the stem being threaded, said chock being formed with a vertical bore to accommodate the stem, and a nut threaded on the upper end of the stem for engagement with the upper face of the chock to maintain the same in clamping engagement with the upper faces of the clamps.

7. In a device of the class described, a pair of complementary rail head engaging clamps, a rod extending transversely through the clamps above the rail, means associated with the rod for cooperation with the clamps to maintain the latter in locked engagement with the head of the rail, a chock having a

wheel-engaging face at one end, and means for mounting said chock for swinging movement in a horizontal plane on the top of the clamps as and for the purpose described, and means associated with one of the clamps for facilitating the disengagement of the clamps from the head of the rail.

In testimony whereof I affix my signature.
FRANCESCO CATIGNANI.
